WATER HEATER AND STEAM GENERATOR

Filed April 25, 1922

Inventor:
Frederick Washington Elyson
By: Herbert J. Ray
Attorney.

UNITED STATES PATENT OFFICE.

FREDERICK WASHINGTON ELLYSON, OF MUNICH, GERMANY.

WATER HEATER AND STEAM GENERATOR.

Application filed April 25, 1922. Serial No. 556,521.

There are known steam generators and water heaters in which, in contradistinction to the boilers with large water space or to smoke-tube boilers, the evaporation is accelerated, and restricted to a relatively small space, by conducting the water which is circulated by a pump or a head through narrow, more or less spirally-shaped passages of circular or oval transverse section, which are heated from their outer side and at one end of which either hot water or steam is discharged, according to the length of the passage and to the temperature of the heating medium.

15 The steam generators and hot-water producers constructed and operating according to that principle are subject to the drawback that the narrow tubes get easily clogged and can no more be cleaned, especially if the 20 clogging is due to incrustation, to oil-soaps resulting from condensed steam or the like.

The present invention relates to a water heater and steam generator based on the above-mentioned principle, but distinguished 25 from the known constructions by the feature that the sectional area of the spirally shaped passage in which the water is exposed to the heat of the heating gases is reduced from below to above so that the 30 water, in flowing through this passage, is heated with increasing rapidity and is, finally, evaporated, the steam being, ultimately, superheated, provided, there be sufficient heat available for this purpose. This may 35 be regulated as required in the various cases.

In order to make my invention more clear, I refer to the accompanying drawing, in which similar numbers of reference denote similar parts throughout the several views, 40 and in which Fig. 1 is an axial section through the threaded inner tube-like body of a constructional example of a steam generator and water heater constructed according to this invention, the left hand half of 45 the figure showing in dotted lines the body or tube in its original cylindrical state, the other half showing the body or tube after it has been turned in such a manner as to form a hollow truncated cone. Fig. 2 is an 50 axial section through the finished steam generating or water heater double-body.

1 (left hand half of Fig. 1) is a cylindrical hollow body consisting preferably of pressed cast iron or the like and having a 55 rolled or milled or cut thread, of which A-B is the outer boundary line. The

thread is turned off in a measure increasing from the one end of the cylinder 1 to the other end, namely corresponding to the line C-D (right hand half of Fig. 1) so that a hollow truncated cone results. A correspondingly shaped tapering tube 2 (Fig. 2) is shoved upon the threaded truncated cone 1 and is firmly connected with it by means of flanges 5 and bolts (not shown). 60 The tube 2 has branches 3 and 4 for connecting it, or the passage or passages of the body 1 respectively, with a supply tube and a discharge tube. 65

Tightening or packing the single convolutions of the helical passage with respect to each other is not necessary because the differences of pressure and of temperature are very small. Even if there should be a slight direct axial communication between two 70 convolutions, or, may be a plurality of such communications or "leaks" that would be of no consequence partly on account of the throttling at the respective place or places, partly on account of the fact that practically 75 all water particles are borne along with the current which circulates more or less quickly through the helical passage which the thread forms. 80

I claim—

1. A water heater and steam generator, comprising, in combination, a thick-walled vertical tube having a helical groove, the sectional area of which is reduced progressively from inlet to outlet, and a shell 85 shoved over said groove.

2. A water heater and steam generator, comprising, in combination, a thick-walled vertical tube tapering in upward direction and having in its outer surface a helical 90 groove, the sectional area of which is reduced in upward direction from a lower inlet to an upper outlet, and a shell fitting 95 said groove.

3. A water heater and steam generator, 100 comprising, in combination, a thick-walled vertical tube tapering in upward direction and having in its outer surface a helical groove of uniform inside diameter, the sectional area of which is thus reduced in up- 105 ward direction from a lower inlet to an upper outlet, and a shell fitting the outside of the tube to close said groove.

In testimony whereof I affix my signature.

FREDERICK WASHINGTON ELLYSON.
